(57) **CLAIM**

The ornamental design for an insulating sleeve for a beverage container, as shown and described.

DESCRIPTION

FIG. 1 is a perspective view of an insulating sleeve for a beverage container showing our new design;

FIG. 2 is a front elevation view thereof;

FIG. 3 is a back elevation view thereof;

FIG. 4 is a right side elevation view thereof, a left side elevation view being a mirror image thereof;

FIG. 5 is a top plan view thereof;

FIG. 6 is a bottom plan view thereof; and,

FIG. 7 is a perspective view of the insulating sleeve for a beverage container shown with the hood in an upright position.

The dot-dash broken lines show environment that forms no part of the claimed design. The evenly dashed broken lines show portions of the insulating sleeve for a beverage container and form no part of the claimed design.

1 Claim, 7 Drawing Sheets
